UNITED STATES PATENT OFFICE.

CLARENCE B. DINSMORE, OF FLINT, MICHIGAN, ASSIGNOR TO A C SPARK PLUG COMPANY, OF FLINT, MICHIGAN, A COMPANY OF MICHIGAN.

LAMP REFLECTOR FOR INSTRUMENT ILLUMINATION.

Application filed September 8, 1927. Serial No. 218,266.

This invention relates to improvements in lamps and more particularly a lamp for the illumination of instruments.

It is an object of this invention to provide an improved and simplified means for mounting a light bulb on the dashboard of an automotive vehicle so that the dials of the various instruments fixed to the dashboard adjacent the bulb will be adequately illuminated. It is a further object of the invention to provide such an arrangement in which a diffused but adequate light will be cast over the various dials so that the operator may see the dials clearly but will not be annoyed by a glaring light.

Other objects and advantages of the invention will appear in the course of the following description, taken in connection with the accompanying drawing and appended claims.

In the drawing—

Fig. 1 is a longitudinal sectional view of the lamp;

Fig. 2 is a section on the line 2—2 of Fig. 1; and

Fig. 3 is a section on the line 3—3 of Fig. 1.

Referring to the drawing, the numeral 10 represents a supporting panel, which may be the instrument board of an automotive vehicle. A base plate 12 is fixed to the panel by screws or rivets 14 and has a beaded or flanged central aperture; and, fitting in this aperture and a corresponding aperture in the panel 10, is a lamp socket 18 held in place by the friction of an outwardly or rearwardly rounded bead 16, U-shaped in transverse section and comprising an inner cylindrical part and an outer cylindrical part respectively adapted resiliently to engage said socket and a lamp hood. Fixed in the socket, by means of a usual bayonet slot 20, a light bulb 22 may be provided, to serve as a light source.

Fitting around the bead 16 is shown a novel lamp cover or hood 24, which may be formed of sheet metal and provided with an outwardly extending bead 26, internally to receive a translucent light-diffusing element such as a celluloid disc 28,—preferably colored and provided with a substantially central aperture 30. The aperture 30 may serve not only to permit expansion and contraction of the mentioned parts during heating

and cooling, thereby obviating distortion of 55 or damage to the disc, but also to direct a restricted beam of white light toward some part of a suitable reflector.

The under side of the cylindrical hood 24, in front of the disc 28 (or to the right thereof, as viewed in Fig. 1) is shown as transversely cut, an under surface of the outer portion thereof being bent inward and upward to provide, from an originally external surface, a re-entrant and parti-cylindrical reflecting surface 25,—adapted to throw the mentioned beam of white light toward the various dials, not shown. The illustrated form of reflecting surface is adapted to produce a downwardly widening area of 70 white light which upwardly terminates in a somewhat crescent-like area of maximum illumination; but the size of the mentioned cut and the shape into which the metal of the hood is pressed, to provide an integral 75 reflector, will naturally depend somewhat upon the arrangement of the dials. All forms of the mentioned reflector may, however, present a straight line profile in longitudinal section and a concave profile in 80 transverse section, substantially as shown; and it will be understood that the described lamp is intended to be so mounted above the mentioned dials that light will be reflected downward and laterally thereto, and not upward to cause glare in the eyes of the driver or passenger.

I claim:

1. In a lamp for instrument boards, a cylindrical hood extending over a lighting element and cut across the under-side, the under-wall being bent inward on a re-entrant curve so that an originally external surface thereof becomes a substantially parti-cylindrical and concave reflecting surface, annular means being formed, on said hood, for supporting a color screen secured across the inside thereof and between the lighting element and the reflecting surface.

2. The combination in a lamp suitable for 100 use upon an instrument board formed with an aperture surrounded by a bead which is U-shaped in cross-section and is rearwardly rounded, a support for a light bulb held within the bead, and a hood supported on 105 a cylindrical surface of the outer side of the bead and provided with a surface for reflecting light generally downward, said

support and said hood being held on said bead by mere fit and friction.

3. In a lamp for instrument boards; a cylindrical hood adapted to extend over a lighting element, said hood being cut across its under-side, and its under-wall being bent

inward on a re-entrant curve and so that an

originally external and cylindrical surface thereof becomes a substantially cylindrical concave and rearwardly reflecting surface 10 for said lighting element.

In testimony whereof I affix my signature.

CLARENCE B. DINSMORE.
